DESIGN FOR A FABRIC FOR LADIES' SHOES AND HANDBAGS OR SIMILAR ARTICLE

William Michaels, New York, N. Y.

Application November 30, 1936, Serial No. 66,198

Term of patent 3½ years

To all whom it may concern:

Be it known that I, William Michaels, a citizen of the United States, residing in New York city, in the county of New York, in the State of New York, have invented a new, original, and ornamental Design for a Fabric for Ladies' Shoes and Handbags or Similar Article, of which the following is a specification, reference being had to the accompanying drawing, forming part thereof.

The figure is a plan view of a piece of shoe fabric showing my new design on an enlarged scale in the ratio of 2 to 1.

I claim:

The ornamental design for a fabric for ladies' shoes and handbags or similar article, substantially as shown and described.

WILLIAM MICHAELS.
